Assistant Examiner — Andrew Kerr(74) *Attorney, Agent, or Firm* — Olav M. Underdal; IDP Patent Services(57) **CLAIM**

The ornamental design for a wine glass, as shown and described.

DESCRIPTION

FIG. 1 is a top perspective view of a wine glass, showing my new design;

FIG. 2 is a top plan view thereof;

FIG. 3 is a right side elevational view thereof, the left side being a mirror image thereof;

FIG. 4 is a front elevational view thereof, the rear being a mirror image thereof;

FIG. 5 is a bottom plan view thereof; and,

FIG. 6 is a cross-sectional view thereof, taken along section line 6-6 of FIG. 2.

1 Claim, 4 Drawing Sheets(56)
